UNITED STATES PATENT OFFICE.

CARLETON ELLIS, OF MONTCLAIR, NEW JERSEY.

ELECTROLYTIC GENERATOR.

1,087,937.

Specification of Letters Patent. Patented Feb. 24, 1914.

Application filed May 29, 1913. Serial No. 770,697.

To all whom it may concern:

Be it known that I, CARLETON ELLIS, a citizen of the United States, and a resident of Montclair, in the county of Essex and State of New Jersey, have invented certain new and useful Improvements in Electrolytic Generators, of which the following is a specification.

This invention relates to electrolytic generators for producing hydrogen and oxygen and relates in particular to a generator having anode and cathode separated by a porous diaphragm all as more fully hereinafter described and as claimed.

15 The accompanying drawings show the apparatus in its preferred form.

In the drawings Figure 1 is a vertical longitudinal section; Fig. 2 is a horizontal longitudinal section and Figs. 3 and 4 are 20 vertical sections.

Like parts are denoted by like characters throughout.

In the drawing 1 is a tank preferably of elongated rectangular shape preferably 25 made of cast iron having the gutter 2 extending around the upper portion thereof and being designated by 3 at the lowest part. This gutter slopes slightly from the end 2 to the end 3 as indicated by the dotted lines.

30 4 is a drain pipe carrying the drain cock 5.

6 is a stand pipe having the gage glass 7 and filling funnel 8.

9 is the top or cover of the generator from which depend the rods 10 held in place by 35 the clamps 11, the whole suspending the anode 15.

13 is a diaphragm which may be of asbestos cloth, the pores of which may be filled with a paste composed of any suitable alkali-resistant filling material. The plate 15 carries the symmetrical T projections which form cells rectangular in shape partly open 40 on one side and of considerable height, producing what may be termed flues along 45 which the generated gas may pass without agitating the entire body of liquid, but producing merely a local agitation along the flues.

The cover is provided with a drainage lip 50 14 and has a depending flange 12 to which the diaphragm sack is fastened by means of bands strapped about the outside of this flange.

17 and 18 are sight feeds, 17 indicating 55 the flow of gas from the anode compart-

ment and 18 the flow of gas from the cathode compartment.

18' is a safety vent for the anode compartment.

19 is a hoisting lug.

20 is a drain cock for the pocket 26 of the gutter 3.

21 is insulation separating and insulating the cover 9 from the lower or cathode portion.

23 are T projections arranged symmetrically along the inner walls of the cathode chamber and forming the cathode flues 25. The pocket 26 is for the purpose of collecting the non-aqueous material which may be 70 spattered or sprayed from the surface of the liquid into the gutter 2 or 3. It should be stated that the said gutter is filled with oil or similar material in preference to water and the aqueous solution falling in the gutter 2 and 3 flows down the incline to the pocket 26. The inclined surface formed by 75 14 in a large measure causes drainage back into the cathode compartment.

27 are stabilizing members widening the 80 base at certain points in order to give greater stability.

In operating this apparatus a solution of say caustic soda or caustic potash of a concentration of 15% or so is placed in the rectangular tank, filling same to a point just below the flange 12 and as shown by the dotted line just above the gutter line; oil is placed in the gutters 2 and 3 so as to constitute a sealing fluid by virtue of the projecting flange which depends into the gutters 2 and 3. The anode is preferably insulated 85 from the cover 9 by insulation 28, although this is not necessary when an oil seal is employed. A current of considerable strength 90 being passed through the apparatus hydrogen is developed in the outer compartment, a large proportion of which is passed up through the cathode flues without serious commotion and in a like manner oxygen is 95 generated in the anode compartment and the gas is collected at the surface without such pressure as would tend to cause the gas to pass through the diaphragm 13 and produce 100 hydrogen and oxygen of such low grade as 105 to be unusable.

The seals 17 and 18 are filled with any suitable liquid through which the gas bubbles and through which the rate of delivery 110 of the gas may be approximately gaged.

The active surface of the anode compartment is preferably two-thirds that of the cathode compartment as such an arrangement permits of more satisfactory delivery of the gas. This may be accomplished by increasing the number of T-shaped ribs carried by the cathode compartment or by employing the same number and increasing the size thereof, or both.

10. The apparatus has the advantage of being very compact while having an enormous generating surface so that with a relatively small apparatus a great output of gas is obtained without contamination to any substantial degree of one gas with the other.

15. The seal 18 preferably is arranged to exert a greater pressure against the outgoing gas than is the seal 17 as indicated by the drawing. This is to be done only when hydrogen of very high purity is required, such for example when making hydrogen for hardening oils, as by exerting a greater pressure in the cathode compartment, there is less tendency of oxygen passing into that compartment. Leakage, if any, is rather in the direction of the anode compartment. With this provision and with the likewise preferred proportioning of the anode to the cathode active surface in the ratio of 2:3, 20 a gas of very desirable purity may be secured.

What I claim is:

1. An apparatus for electrolytically generating hydrogen and oxygen which comprises a rectangular receptacle having T shaped projections on its inner walls, a cover therefor and depending from said cover an anode consisting of a plate having T shaped projections symmetrically disposed along its 25 surface and paralleling the T shaped projections of the cathode wall.

2. An apparatus for electrolytically generating hydrogen and oxygen which comprises a rectangular receptacle having T shaped projections on its inner walls, a cover therefor and depending from said cover an anode consisting of a plate having T shaped projections symmetrically disposed along its surface and paralleling the T shaped projections of the cathode wall and having a gutter disposed along the sides of said generator for the removal of spray.

3. An apparatus for electrolytically generating hydrogen and oxygen which comprises a rectangular receptacle having T shaped projections on its inner walls, a cover therefor and depending from said cover an anode consisting of a plate having T shaped projections symmetrically disposed along its 30 surface and paralleling the T shaped projections of the cathode wall, the ratio of the active surface of the anode to the cathode being substantially 2:3.

4. An apparatus for electrolytically generating hydrogen and oxygen which com-

prises a rectangular receptacle having T shaped projections on its inner walls, a cover therefor and depending from said cover an anode consisting of a plate having T shaped projections symmetrically disposed along its 35 surface and paralleling the T shaped projections of the cathode wall; the cathode compartment being adapted to maintain a slightly higher pressure than the anode compartment; whereby hydrogen of high purity 40 is secured.

5. An apparatus for electrolytically generating hydrogen and oxygen which comprises a rectangular receptacle having T shaped projections on its inner walls, a cover therefor and depending from said cover an anode consisting of a plate having T shaped projections symmetrically disposed along its 45 surface and paralleling the T shaped projections of the cathode wall; the cathode surface being of 50% greater area than the anode surface and the cathode compartment being adapted to be maintained under a pressure higher than that of the anode compartment; whereby hydrogen gas substantially 50 free from oxygen is secured.

6. An apparatus for electrolytically generating hydrogen and oxygen which comprises a rectangular guttered receptacle having substantially T shaped projections on its inner walls, a cover therefor and depending from said cover an anode consisting of a plate having substantially T shaped projections symmetrically disposed along its 55 surface and paralleling the T shaped projections of the cathode wall; whereby gas flues are formed assisting in the delivery of the gas without undue commotion.

7. Apparatus of the character described, comprising an outer receptacle constituting an electrode and provided with internally arranged upstanding T-shaped ribs affording upstanding channels therebetween open at corresponding sides and upper ends, a plate mounted within the receptacle constituting an electrode of opposite polarity and provided upon opposite sides thereof with upstanding T-shaped ribs affording upstanding channels therebetween open at corresponding sides and upper ends, and a 60 casing surrounding the inner electrode.

8. Apparatus of the character described, comprising an outer receptacle constituting an electrode and provided with internally arranged upstanding spaced substantially T-shaped ribs, a plate mounted within the receptacle constituting an electrode of opposite polarity and provided with upstanding spaced substantially T-shaped ribs, and means surrounding the plate and dividing 65 the receptacle into inner and outer chambers.

9. Apparatus of the character described, comprising an outer receptacle serving as an electrode, a trough surrounding the up-

per portion of the receptacle and having its bottom wall horizontally inclined downwardly toward one end of the receptacle, a cover for the receptacle suitably mounted 5 upon the upper end of the trough, a depending flange carried by the cover and arranged between the wall of the trough and the upper end of the receptacle to form a liquid seal therewith, and a deflector flange 10 depending from the cover and arranged in-

wardly of and adjacent the upper end of the receptacle.

Signed at Montclair in the county of Essex and State of New Jersey this 23rd day of May A. D. 1913.
